UNITED STATES PATENT OFFICE.

RICHARD E. PERKINS, OF JOPLIN, MISSOURI.

FOUNTAIN-PEN.

1,369,184.

Specification of Letters Patent. Patented Feb. 22, 1921.

Application filed January 19, 1920. Serial No. 352,381.

To all whom it may concern:

Be it known that I, RICHARD E. PERKINS, a citizen of the United States, residing at Joplin, in the county of Jasper and State of Missouri, have invented certain new and useful Improvements in Fountain-Pens, of which the following is a specification, reference being had to the accompanying drawings.

- 10 This invention relates to certain improvements in fountain pens, and it is an object of the invention to provide a device of this general character having novel and improved means including a reservoir, together with means whereby said reservoir may be conveniently and effectively filled from the writing end portion of the device. Another object of the invention is to provide a novel and improved device of this 20 general character wherein the barrel comprises two separable sections and which sections normally inclose a reservoir carried by said sections and wherein means are provided so that upon relative longitudinal 25 movement of the sections of the barrel, writing fluid may be drawn within the reservoir through the writing end portion of the instrument.

An additional object of the invention is 30 to provide a novel and improved device of this general character embodying two relatively movable members in telescopic engagement, one of said members constituting a reservoir provided with a normally 35 closed opening in its end portion remote from the writing end of the device and wherein the second member constitutes a suction element whereby upon relative movement of the members in one direction, 40 the opening in the reservoir is opened and the writing fluid drawn into the reservoir through the writing end of the device.

Furthermore, it is an object of the invention to provide a novel and improved device 45 of this general character comprising two relatively movable members telescopically engaged one within the other, one of said members constituting a reservoir and the second of said members constituting a suctioning element whereby relative movement of 50 said members in one direction creates a vacuum whereby writing fluid may be caused to enter within the reservoir through the writing end of the implement.

55 The invention consists in the details of construction and in the combination and ar-

angement of the several parts of my improved pen whereby certain important advantages are attained and the device rendered simpler, less expensive and otherwise 60 more convenient and advantageous for use, as will be hereinafter more fully set forth.

The novel features of my invention will hereinafter be definitely claimed.

In order that my invention may be the 65 better understood, I will now proceed to describe the same with reference to the accompanying drawings, wherein:

Figure 1 is a view partly in longitudinal section and partly in elevation of a fountain 70 pen constructed in accordance with an embodiment of my invention.

Fig. 2 is an enlarged fragmentary sectional view taken longitudinally through the end portion of the pen remote from the 75 writing end thereof and with the cap omitted; and

Fig. 3 is a view in top plan of the element 80 herein employed for maintaining the compressible gasket in applied position.

As disclosed in the accompanying drawings, B denotes the barrel of my improved pen consisting of two separable sections, 1 and 2. Coacting with the adjacent end portions of the sections 1 and 2 is the coupling 85 sleeve 3 having its central portion internally threaded for engagement with the external threads produced on the adjacent ends of the sections 1 and 2 and as is particularly illustrated at 4 in Fig. 1. The coupling 90 sleeve 3 serves to effectually maintain the sections 1 and 2 in assembled relation yet at the same time, permits the same to be readily separated for a purpose to be hereinafter more particularly referred to.

In the present embodiment of my invention, the section 1 constitutes the writing end portion of the barrel B and extending within the bore of said section 1 and carried thereby is a tubular member 5 of fixed formation and preferably made of metal. This member 5 constitutes a reservoir to contain a desired quantity of writing fluid and the end portion of the member 5 inserted within the section 1 of the barrel B is open but is 95 closed by the inserted end portion of the feed bar F arranged within the outer portion of the bore of the section 1. Coacting with the feed bar F in a conventional manner is the nib or pen point N. While the 100 feed bar F may be of any type which will 105 fully comply with the requirements of prac-

tice, I particularly prefer that the bar F be of the same general character as the feed bar embodied in my co-pending application executed on even date herewith.

5 The member 5 is of such length that when the sections 1 and 2 of the barrel B are in assembled or connected relation, the outer end of said member 5 will terminate in close proximity to but spaced from the outer end 10 of the barrel B whereby a chamber *a* is provided and which chamber may be termed a vacuum chamber.

Initially the outer end of the member 5 is open but the same has snugly engaged there-in 15 a cupped plug or cap 6, the open face of said plug or cap 6 being outwardly directed. This plug or cap 6 may be maintained in applied position in any desired manner but in the present embodiment of my invention, 20 I show said plug or cap 6, as at 7, in threaded engagement with the adjacent end portion of the member 5.

The base of the plug or cap 6 is provided with a plurality of restricted ports 8 normally closed by the valve 9 positioned within 25 the cupped plug or cap 6. The valve 9 is preferably of rubber or kindred yieldable material and is constantly urged into closed position through the instrumentality of the 30 expandible member 10. The member 10 is herein disclosed as a coil spring encircling an outstanding shank 11 secured to substantially the axial center of the base portion 6^a of the plug or cap 6 and said spring 35 is interposed between the valve 9 and a disk or plate 12 disposed from the open face of the plug or cap 6. This plate 12 is preferably of the same diameter as, or slightly less diameter than, the bore of the section 2 of 40 the barrel and extends upon and contacts the upper edge of the hollow member or reservoir 5. The disk or plate 12 is of such diameter as to have contact with the outer or free margin or edge of the plug or cap 6 and 45 is held in such position through the medium of the shank 11, which shank constitutes a headed screw or bolt with the threaded portion in engagement with the base of the plug or cap 6 and the head coacting with the disk 50 or plate 12 as is clearly illustrated in Fig. 2. The disk or plate 12 is also provided with a plurality of restricted ports 14 affording communication between the interior of the plug or cap 6 and the vacuum chamber *a* 55 hereinbefore referred to. It is to be noted at this time that when the valve 9 opens, it moves outwardly of the barrel B or in a direction away from the writing end thereof.

The outer end of the barrel B or the end 60 thereof remote from the writing end of the barrel is initially open but is adapted to be normally closed by a cap 15 herein disclosed as of a screw type. Snugly engaged within the outer end portion of the barrel B 65 or more particularly the section 2 of said

barrel is a cupped plug or cap 16 having its open face also outwardly directed. The plug or cap 16 is preferably in duplicate of the plug or cap 6 so that the same may be readily interchanged or more particularly to facilitate the assembly of my pen as it will not require either of the plugs or caps 6 or 16 to be of particular structure other than that hereinbefore described with respect to the plug or cap 6. For this reason 70 the upper extremity of the bore of the section 2 of the barrel or that portion thereof forming the upper end of the vacuum chamber *a* is restricted to such size that it is of the same size as the bore of the hollow member 5, 75 thereby forming at the upper end of the vacuum chamber a shoulder *b*. The plug or cap 16 may be held within the section 2 of the barrel B in any desired manner but, as herein embodied, said cap is maintained 80 in applied position, as indicated at 17 by threads.

Overlying the outer or open face of the plug or cap 16 is a disk or plate 18 having contact with the outer or free margin or 90 edge of said plug or cap 16 and held in such position by the headed shank 19, also having threaded engagement with the central portion of the base of the plug or cap 16.

The base 16^a of the plug or cap 16 is provided with a plurality of restricted ports 20 affording communication between the interior of said plug or cap 16 and the vacuum chamber *a*. These ports 20 are normally closed by the valve 21 arranged within the 100 plug or cap 16 and said valve 21 is normally maintained in closed position by the expandible member 22 herein disclosed as a coil spring encircling the shank 19 and interposed between the valve 21 and the disk or 105 plate 18. The valve 21 is also preferably of rubber or kindred material.

The disk or plate 18 is provided with the restricted ports 23 which afford communication between the interior of the plug or 110 cap 16 and a recess or pocket 24 produced in the inner face of the cap 16. Leading from the recess or pocket 24 and extending through the cap 15 to the atmosphere is a 115 port 25.

26 denotes a cap herein disclosed as of a slip type which coacts with the opposite end portions of the barrel B in a well known manner, and said cap 26 is also provided with the vent openings 27 as is well known.

Surrounding the member 5 and positioned between the inner or adjacent ends of the sections 1 and 2 of the barrel is a gasket 28 of rubber or other yieldable or expandible material, and said gasket 28 is held against the adjacent end of section 2 of the barrel by a washer 29 loosely surrounding the member 5 but having its periphery in threaded engagement with the internal threads of the coupling sleeve 3. The washer 29 not only 120

serves to maintain the gasket 28 in applied position but can be readily manipulated to cause the desired extension of the gasket 28 to assure the requisite coaction or contact of 5 said gasket 28 with the member 5.

The washer 29 may be applied in any desired manner but, as is particularly illustrated in Fig. 3, it is provided with the diametrically opposed recesses or openings 30 10 to provide means whereby a spanner wrench or other suitable implement may be engaged therewith to impart the desired rotation thereto.

Normally the sections 1 and 2 of the pen 15 are in the assembly as illustrated in Fig. 1 of the accompanying drawings. When it is desired to fill the member or reservoir 5, the section 1, upon relative rotation of the sections 1 and 2, is disengaged from the coupling sleeve 3 whereby the sections 1 and 2 20 are capable of relative longitudinal movement. Upon such movement in one direction, a vacuum is created in the chamber *a* which chamber is increased during such 25 movement. This vacuum results in holding the valve 21 in closed position and opening the valve 9. Resultant suction effected by the vacuum results in the writing fluid being drawn into the reservoir 5 through the 30 writing end of the pen or through the delivery conduits (not shown) in the feed bar F. When the sections 1 and 2 are relatively moved in the opposite direction or one toward the other, the valve 9 closes and the 35 valve 21 opens whereby the chamber *a* is placed in communication with the atmosphere and such last named movement accomplished without resistance.

If the reservoir 5 is not sufficiently filled 40 upon one stroke of the sections 1 and 2, the same can be repeated until the desired filling of the reservoir is accomplished.

In order to prevent ingress of air within the member 5 and also to clearly indicate 45 when the member or reservoir 5 is sufficiently filled, I find it of utmost importance to arrange within said member or reservoir 5 a buoyant body 31, of any desired material. This member or body 31 rises with the 50 liquid level within the member or reservoir 5 and also serves as a valve so that when the same, under the influence of the rising column of fluid within the member or reservoir 5, contacts with the base of the plug 55 or cap 6, the ports 8 within said base portion are effectively closed and sealed. When the member or body 31 closes the ports 8, the relative separating movement of the sections 1 and 2 of the barrel B is checked so that the 60 operator at once knows that the member or reservoir 5 has been sufficiently filled with the writing fluid. The body 31 is provided in its upper surface with a recess 32 adapted to accommodate the enlargement formed 65 on the under surface of the cup shaped mem-

ber 6 for the reception of the valve guide 11 thereof, and this recess 32 communicates with a vertical opening 33 extending axially through the body 31 which permits the escape of any pocketed air. 70

It is to be understood that during a filling operation, the wiring end portion of the pen is submerged or inserted within a source of writing fluid supply.

In order that the function of the washer 75 29 may be fully established, I wish to say that as the working face of the gasket 28 becomes worn as the result of continued use, the movement of the washer 29 toward the adjacent end of the section 2 of the barrel 80 will result in a further expansion of the gasket 28 so that the desired engagement of such gasket with the periphery of the member 5 may be restored.

It is to be noted that the tubular member 85 5 is of substantially uniform size throughout its length and is accordingly free from any projections which will prevent its withdrawal from the section 2 of the barrel for the purpose of cleansing or repairing. In 90 fact, construction of the upper end of the barrel section 2 and of the tubular member 5 is such as to render any necessary repairs extremely simple and expeditious.

The end portion of the member 5 inserted 95 within the section 1 of the barrel B may be positively held within said section 1 in any desired manner but preferably through the instrumentality of an adhesive medium.

From the foregoing description, it is 100 thought to be obvious that a pen constructed in accordance with my invention is particularly well adapted for use by reason of the convenience and facility with which it may be assembled and operated, and it will also 105 be obvious that my invention is susceptible of some change and modification without departing from the principles and spirit thereof, and for this reason, I do not wish to be understood as limiting myself to the precise 110 arrangement and formation of the several parts herein shown in carrying out my invention in practice except as hereinafter claimed.

It is also to be understood that the gasket 115 28 can be readily expanded for requisite contact with the periphery of the member 5 by relative rotation of the section 2 and the coupling sleeve 3 so that, at all times, an adjustment of the washer 29 is unnecessary. 120

I claim:—

1. A fountain pen comprising a barrel divided transversely into two sections, means for coupling said sections, a rigid hollow member carried by one of the sections and 125 telescopically engaged with the second section, said hollow member constituting a reservoir, said hollow member having its outer end spaced from the adjacent end of the second section when said sections are 130

coupled whereby a vacuum chamber is afforded therebetween, said adjacent ends of the hollow member and second section of the barrel being provided with normally closed ports, the port in the hollow member opening and the port of the second section closing upon separating movement of the sections and vice versa, said separating movement of the sections creating a vacuum in the chamber.

2. A fountain pen comprising a barrel divided transversely into two sections, means for coupling said sections, a rigid hollow member carried by one of the sections and telescopically engaged with the second section, said hollow member constituting a reservoir, said hollow member having its outer end spaced from the adjacent end of the second section when said sections are coupled whereby a vacuum chamber is afforded therebetween, said adjacent ends of the hollow member and second section of the barrel being provided with normally closed ports, the port in the hollow member opening and the port of the second section closing upon separating movement of the sections and vice versa, said separating movement of the sections creating a vacuum in the chamber, and means operable under the influence of the fluid within the hollow member for closing the port in said member.

3. In a fountain pen, the combination with a barrel comprising two sections longitudinally alined, means for detachably coupling adjacent end portions of said sections, a hollow member carried by one of the sections and telescopically engaged with the other section, said hollow member being provided with an opening for the ingress or egress of writing fluid, a cupped plug fitting within the outer end portion of the hollow member and provided with a port in communication with the interior of the hollow member, a valve positioned within said cupped plug and normally closing the port and a port in the adjacent end of the second section of the barrel and a valve normally closing said last named port, and a buoyant body within the hollow member inwardly of the plug, said buoyant body closing the opening in the plug when at the limit of its movement toward the plug.

4. In a fountain pen the combination with a barrel comprising two sections longitudinally alined, a hollow member carried by

one of the sections and telescopically engaging the other section, said hollow member constituting a reservoir, check valves disposed in the outer ends of said hollow member and of the barrel section with which it is telescopically engaged, a coupling sleeve adapted to detachably connect the adjacent end portions of said barrel sections, a compressible member surrounding said hollow member and a washer surrounding said hollow member abutting said compressible member and adjustably engaging said coupling sleeve, said compressible member being disposed intermediate said washer and the end of said section with which said hollow member is telescopically engaged.

5. In a fountain pen, the combination with a barrel comprising two sections longitudinally alined, a hollow member carried by one of the sections and telescopically engaged with the second section, a check valve arranged within the bore of said hollow member at the end thereof telescopically engaging with the second barrel section, the bore of said barrel section being reduced at its outer end and being of the same diameter as the bore of said hollow member, and a second check valve similar to said first named check valve disposed within the reduced portion of the bore of said second section and opening in the same direction as the check valve in the end of said hollow member.

6. In a fountain pen the combination with a barrel comprising two sections longitudinally alined, means for detachably coupling the adjacent ends of said sections, a hollow member arranged within the bore of one of said sections and secured thereto and telescopically engaging in the bore of the other of said sections, said hollow member being of uniform diameter throughout its length, a valve disposed in the end of said hollow member telescopically engaging in the bore of said last named section and a check valve disposed in the outer end of said last named section, said check valves opening in the same direction and being adapted when the last named section of the barrel is reciprocated with relation to said hollow member to coact to form a vacuum within said hollow member.

In testimony whereof I hereunto affix my signature.

RICHARD E. PERKINS.
